UNITED STATES PATENT OFFICE.

CARL F. ANDERSON, OF WEST NEW YORK, NEW JERSEY.

RATCHET WRENCH AND DRILL.

SPECIFICATION forming part of Letters Patent No. 659,564, dated October 9, 1900.

Application filed January 17, 1900. Serial No. 1,817. (No model.)

To all whom it may concern:

Be it known that I, CARL F. ANDERSON, a citizen of the United States, residing at West New York, in the county of Hudson and State 5 of New Jersey, have invented a certain new and useful Ratchet Wrench and Drill, of which the following is a specification, reference being had therein to the accompanying drawings.

10 This invention relates to ratchet wrenches and drills; and the object in view is to provide a simple and effective device for imparting intermittent rotary motion to a drill or boring-bit, at the same time enabling the handle member of the device to engage bits or 15 chucks of different sizes and shapes, the device being further adapted for use as a ratchet-wrench. The device also embodies ratchet-controlled mechanism by means of which the 20 boring-bit or drill-point may be actuated or turned in either direction.

Other objects and advantages of the invention will appear in the course of the ensuing description.

25 In the accompanying drawings, Figure 1 is a side elevation of a combined ratchet drill and wrench constructed in accordance with the present invention. Fig. 2 is a top plan view of the same. Fig. 3 is a bottom plan 30 view thereof. Fig. 4 is a vertical longitudinal section through the same, showing a drill-point and a drill-chuck applied to the rotatable head of the device. Fig. 5 is a plan view of the stock of the implement with the rotatable head removed. Fig. 6 is a plan view 35 of the thread-cutting die. Fig. 7 is a detail perspective view of the chuck detached, omitting the sleeve. Fig. 8 is a detail perspective view of the chuck-sleeve. Fig. 9 is a detail 40 tail cross-section through the rotatable head of the implement, showing one of the jaws in elevation. Fig. 10 is a bottom plan view of the rotatable head. Fig. 11 is a detail perspective view of one of the jaws carried by 45 the rotatable head.

Similar numerals of reference designate corresponding parts in all the figures of the drawings.

In the drawings, 1 designates the stock of 50 the implement, which is provided with a detachable handle 2, which is adjustable to different portions of the stock. For this pur-

pose the stock is provided with a longitudinally-extending reduced shank 3 and a laterally-extending shank 4. These shanks are 55 preferably screw-threaded, and the handle 2 is provided with an interiorly-threaded socket by which it is adapted to fit over one or the other of the shanks 3 or 4, as may be necessary, to adapt the device to different kinds of 60 work and to enable the operator to hold the drill in different positions.

The stock 1 is recessed, as shown at 5, to allow the rotatable head 6 of the implement to be mounted therein. The head proper (indicated at 6) is seated in a circular rabbet 7 in the stock and is provided with a reduced portion 8, which fits and rotates within a cylindrical recess in the stock and is provided with peripheral ratchet-teeth 9, which are 70 adapted to be engaged by a pair of sliding dogs 10, mounted in longitudinal recesses 11 in the stock and normally urged toward the ratchet-teeth 9 by means of expansion-springs 12, arranged behind the dogs. Each of the 75 dogs is further provided with a laterally-extending operating and keeper pin 13, which works in a slot 14 in the stock, thus enabling the dog to be retracted or drawn out of engagement with the ratchet-teeth. Each slot 80 is also provided at one end with an L-shaped extension 15, which provides a shoulder 16, against which the pin 13 may rest for holding the dog out of engagement with the ratchet-teeth 9. The construction just described 85 enables either one of the dogs to be held out of engagement, while the other dog engages the ratchet-teeth 9 and permits the rotatable head to be turned in one direction. By reversing the positions of the dogs the 90 rotatable head may be caused to turn in the opposite direction in a manner that will be readily understood.

The head 6 is provided with a shank 17, which passes through the stock 1 and is provided with an annular groove 18, adapted to receive a pivoted locking-plate 19, pivoted to the stock at the point 20 and provided with a semicircular notch 21, adapted to snugly embrace the shank 17 and fit within the groove 100 18, thus preventing accidental displacement of the rotatable head. The free end of the locking-plate 19 terminates in an oblique abutting edge 22, which comes in contact with

an oblique shoulder 23 at the side of the stock, said shoulder being formed by a reinforcing-rib 24, formed on that side of the stock, as fully shown in Fig. 3. The locking-plate 5 is further provided with an opening 25 to receive a fastening-screw 26, which fixes the locking-plate and maintains the engagement between said plate and the shank of the rotatable head.

10 The extremity of the shank is squared, as shown at 27, to receive a thimble 28, having a squared socket to fit over the part 27 and adapted to be secured thereto by means of a retaining-screw 29. The outer end of the 15 thimble is threaded to receive the drill-point or boring-bit 30, which has a screw-threaded socket 31 to engage with the screw-threaded portion of the thimble 28. This enables drill-points of different kinds to be associated with 20 the thimble and with the device as a whole.

The rotatable head 6 is provided in its outer portion with an oblong recess 32, extending longitudinally, within which are oppositely-located guide-ribs 33, having inwardly-diverging adjacent faces 34, thus forming a dovetailed recess or channel adapted to slidably receive and engage the dovetailed shanks 35 of a pair of sliding and adjustable jaws 36, preferably provided with flat inner faces, whereby they are adapted to engage either the square shank of a drill-point or boring-bit or a chuck, at the same time enabling said jaws to be used upon a nut in the capacity of a wrench. Passing longitudinally through 35 the recess 32 and through the end walls of the head is a jaw-setting screw and chuck-key combined. This screw (indicated at 37) is provided at opposite sides of its center with right and left hand threads, as shown, and 40 passes through correspondingly-threaded openings 38 in the shanks of the jaws 36, so that by turning said screw the jaws may be moved toward or away from each other to clamp any object which is placed between 45 them.

The guide-ribs 33 are centrally cut away, as shown at 39, to receive between them the shank 40 of a chuck 41, and the shank 40 is provided in its inner end with a notch 42, 50 adapted to receive the screw 37, which thus acts in the nature of a key and prevents the chuck from rotating independently of the rotatable head, thus securing an interlocked engagement between the chuck and head, 55 forcing said parts to rotate together. The chuck 41 may otherwise be of the ordinary construction, involving the jaws 43 and jaw-operating sleeve 44. In order to prevent displacement of the chuck, the retaining-screws 60 45 are provided, said screws passing through the rotatable head at opposite points and entering threaded holes in the shank of the chuck. From the foregoing description it will be seen that the screw 37 acts in the double capacity of an adjusting device for moving the jaws 36 and a key for holding the

chuck against rotary movement with relation to the rotatable head.

The outer portion of the stock 1 is provided with a longitudinal recess 46, in which is arranged a thread-cutting die 47 in the form of a disk having thread-cutting openings 48 of different sizes. This disk is centrally journaled by means of a removable pivot-screw 49, which passes through a central opening 50 in the thread-cutter and through corresponding openings in the stock. The stock is also provided at its end with oppositely-located recesses 51, and any one of the openings 48 may be brought into line with the recesses 51 when it is desired to use the thread-cutting part of the implement. The thread-cutter may be locked in any of its operative positions by means of a set-screw 52, passing through the stock 1 and engaging against the 85 adjacent surface of the thread-cutting disk in a manner that will be readily understood.

From the foregoing description it will be seen that I have provided a combined ratchet drill and wrench which is adapted to have 90 associated therewith drill points and chucks of different sizes and shapes and in which the chuck or drill-point engaging jaws may be utilized as wrench-jaws for grasping and operating upon nuts, bolt-heads, &c. It will also be seen that the rotatable head may be operated in either direction by manipulating the dogs which are carried by the stock and which operate in connection with said head.

I do not desire to be limited to the precise 100 details of construction hereinabove set forth, as it will be apparent that many changes may be made in the form, proportion, and minor details of construction without departing from the principle or sacrificing any of the advantages of the invention.

Having thus described the invention, what is claimed as new, and desired to be secured by Letters Patent, is—

1. A combined ratchet drill and wrench 110 comprising a stock, a rotatable head carried thereby and having a shank provided with an annular groove, a flat locking-plate pivotally mounted on one side of the stock and adapted to be swung into engagement with 115 said groove to lock the head against endwise movement in both directions while leaving it free to rotate, and a fastener carried by the locking-plate and adapted to engage the stock, substantially as described. 120

2. A combined ratchet drill and wrench comprising a stock, a rotatable head, a locking-plate for holding the head in the stock, 125 sliding jaws fitted in the head, a chuck having a notch in the end of its shank, and a combined jaw-setting screw and chuck-key passing through the head and jaws and also through the notch in the shank of the chuck, substantially as specified.

3. A combined ratchet drill and wrench 130 comprising a stock, a rotatable head carried thereby and provided with a recess, a piv-

oted locking-plate on the stock for holding it therein, guide-ribs at opposite sides of the recess, jaws slidingly fitted to said ribs, a drill-chuck having a notched shank fitted in said recess, and a centrally-arranged combined jaw-setting screw and drill-chuck key passing through the head and extending across the recess and also entering the notch

in the shank of the chuck, substantially as described.

In testimony whereof I affix my signature in presence of two witnesses.

CARL F. ANDERSON.
